KEY AND PERMUTATION OPERATED LOCK

William E. Hamilton, Evanston, Ill., assignor to Dudley Lock Corporation, Chicago, Ill., a corporation of Illinois

Application September 12, 1940, Serial No. 356,489

10 Claims. (Cl. 70—285)

This invention relates to locks of the type which include a combination mechanism by which the bolt or locking member is operable, and a key operated mechanism which independently actuates such locking member.

One object of the invention is to provide a simple and reliable mechanism of sturdy construction.

Another object is to provide a lock in which the locking member may be operated either by the combination alone or by means of the key alone.

A further object is to provide improved means controlled by the key operated mechanism and adjustable for altering the position of the dial relative to the combination mechanism so as to change the effective operating combination of the lock at will.

It is also an object of the invention to provide means for insuring a full throw of the bolt in either direction after it has been partially moved in that direction.

The invention also includes an improved and simplified mechanism for automatically upsetting the combination in the process of operating the bolt to insure that the mechanism shall be left locked whenever the bolt is thrown to locking position.

Other objects and advantages will appear as the description proceeds. The invention consists of certain features and elements of construction in combination, as herein shown and described and as indicated by the claims.

In the drawings:

Figure 1 is a front elevation of a case for a lock embodying this invention, showing the case with most of the parts removed but with the operating cam and follower plate in position for actuating the bolt.

Figure 2 is an elevational view similar to Figure 1 but showing a partition plate and a bolt controlling detent dog added in their places.

Figure 3 is a rear face view of the bolt removed from the case and showing an abutment thereon which cooperates with the dog shown in Figure 2.

Figure 4 is a front elevation of the case showing the bolt in position, together with one of the locking tumblers and parts cooperating therewith.

Figure 5 is a view similar to Figure 4 but showing the parts as positioned in the process of moving the bolt to locking position.

Figure 6 is a substantially axial vertical section through the lock mechanism and its op-

erating knob and key plug, the knob and key plug being separated as a unit assembly from the lock mechanism and its case, and a portion of a door panel being shown interposed, ready for the assembly of the lock parts on opposite sides thereof.

Figure 7 is a transverse section taken substantially as indicated at line 7—7 on Figure 6.

Figure 8 is a section similar to Figure 7 but showing the parts in release position to allow resetting of the knob.

Figure 9 is a transverse section taken as indicated at line 9—9 on Figure 6 and showing the position of certain tumblers of the key plug when the regular service key is inserted therein.

Figure 10 is a section similar to Figure 9, showing the positions assumed by certain tumblers when the reset key is inserted.

Figure 11 is a detail face view of the tumbler driving member.

Figure 12 shows a modification of certain parts shown in Figure 2.

The type of cabinet lock to which this invention relates is applicable to a wide variety of uses, but is perhaps most commonly employed on lockers for schools and other institutions. In such cases the lock is operated by means of the combination mechanism so that the student or other user of the locker need not carry any key. However, all the locks in a group or in a given installation may be operable by a master key, and with the construction herein shown and described the key operated mechanism may also be employed through the agency of a special reset key to release the operating knob from the combination mechanism and permit it to be readjusted with relation thereto for changing the effective combination, as, for example, at the beginning of a new school year, or whenever a locker is released by one user and taken over by another.

Figure 1 shows the rectangular case 1 which houses the lock mechanism and which is provided with ears or flanges 2 at opposite ends for attachment to the door or other closure on which it is to be used. The locking member is a slideable bolt 3 which is seen in Figures 3, 4 and 5, but which is omitted from Figure 1. For key operation the bolt is actuated by means of a rotatable spindle 4, carrying fixed near its lower end, a cam member 5 cooperating with a follower in the form of a sliding plate 6, fitted into the case 1. The cam 5 is substantially segmental in form, having contact points 7 and 8 at opposite ends of its arcuate edge 9. The point 8 bears against a cooperating straight surface 10 which

forms a portion of the outline of an opening in the follower plate 6, and when the spindle 4 is turned in clockwise direction the point 8 of the cam, riding against the surface 10, moves the plate to the right in Figure 1, which is the direction for shifting the bolt from locking to unlocking position. The lower end of the surface 10 at 11 adjoins another straight surface 12 in the plate, which is substantially perpendicular to the direction of movement so that when the point 8 of the cam passes the point 11 on the follower plate, the arcuate portion 9 of the cam merely rides against the point 11 without causing any further travel of the plate 6. In Figure 1 the plate 6 is shown in dotted outline at the limit of movement thus caused by the cam 5; it is shown in full lines at the opposite limit of its travel in the case. It may be explained that the movement of the point 8 of the cam in contact with the portion 10 of the follower, represents the normal rotation caused by the master key for opening the lock; the additional movement of the arcuate portion 9 in contact with the point 11 occurs only when the reset key is employed for the special purpose of re-adjusting the operating knob of the combination mechanism.

The return movement of the plate 4 for shifting the bolt to locking position is partly accomplished by reverse rotation of the cam with its radial edge 13 riding against the corner 14 of the follower plate opening. As the radial edge 13 comes into alignment with the vertical edge 15 of the opening, the drive is taken up by the contact point 1 of the cam bearing against this edge 15 and continues until the parts are returned to the positions shown in Figure 1.

Throughout the movement of the cam 5 and follower plate 6 these two parts are positively inter-engaged because the slope or obliquity of the face 10 is such that while the point 8 of cam 5 is riding along the surface 10 the opposite side of the cam positively engages the plate either by contact of the point 7 with the face 15 or by contact of the point 14 with the edge 13 of the cam. And at the limit of throw the inner edge 16 of the plate 6 abuts the inner face of the wall of the casing 1 and is held thereto by engagement of the arcuate edge 9 of the cam with the edge 12 of the opening in the follower plate.

The sliding movement of the plate 6 is transmitted to the bolt 3 by means of an upstanding lug 17 which extends between a lug 18 on the bolt and the end surface 19 of a pawl 20 secured to the bolt by a pivot 21. As shown in full lines in Figure 4, the pawl 20 is normally held in engagement with the lug 17 by contact of the nose 22 of the pawl with the circular peripheries of the disk tumblers of the combination mechanism, one of which is seen at 35 in Figure 4. A spring 24 normally presses the nose 22 of the pawl against these circular edges of the tumblers; but when the tumblers are adjusted in accordance with the "combination" of the lock their notches are aligned with each other and registered with the nose 22 of the pawl so that its spring 24 swings the pawl into the notches and out of engagement with the lug 17, as indicated in dotted lines in Figure 4. Of course, this occurs only when the lock is operated through the combination mechanism. When the key actuated mechanism is employed it rotates the spindle 4 and its cam 5 to shift the plate 6, whereupon the upstanding lug 17 of the plate engages the lug 18 of the bolt to withdraw the bolt from locking position. Upon reverse rotation of the spindle 4

5 and cam 5 the upstanding lug 17 of the plate transmits a thrust through the pawl 20 and its pivot 21 to the body of the bolt 3 for projecting it into locking position.

Between the bolt itself and the follower plate 6 there is secured in the casing a partition plate 27 having a clearance opening 28 through which the lug 17 projects, and which is dimensioned to accommodate the movement of the lug when the plate 6 is actuated by its cam 5. When the bolt 3 is installed in the casing 1 it is turned over from the position shown in Figure 3 so that its face, which appears in that view lies adjacent the partition plate 27. A bearing rib 3a at one edge of the bolt, and a bearing portion 29 at the opposite edge, actually rest upon the plate 27 and slide over it as the bolt is moved. The rib 3a includes an abutment 30, and there is pivoted on the plate 27 at 31 a detent 32 having oblique faces 33 and 34 which intersect each other and which successively engage the abutment 30 as the bolt is shifted in the casing. A spring 32a presses the detent 32 firmly into engagement with the abutment 30 so that, for example, in the initial portion of the unlocking movement the abutment 30, riding against the oblique face 33, forces the detent to swing about its pivot 31 and stresses the spring 32a. The energy thus stored in the detent 32 is released as the abutment passes the end of the oblique face 33 and engages the oppositely oblique face 34. At this point the energy of the spring operates to force the detent face 34 to act as a cam against the rounded portion of the abutment 30 so as to drive the bolt through the remainder of its range of travel, insuring that it shall not be left at an intermediate position. When the bolt is moved in the opposite direction a similar action takes place, the abutment first crowding the detent aside by riding along the inclined surface 34, and then being itself driven by the cam action of the inclined surface 33 as the energy stored in the spring 32a is released.

The operation of the combination mechanism for actuating the bolt is largely similar to that of previous structures. There are three tumblers, indicated in Figure 6 as 25, 35 and 45. They are rotatively carried on a hollow post 36 which is secured rigidly in the partition plate 27. Internally, the post serves as a journal bearing 50 for the cylindrical portion of the spindle 4, and externally, as a bearing for the tumbler disks. Suitable spacer washers 37 are interposed between the disks, and the usual driving connections between the disks consist in lugs 38 upstanding from their faces all at substantially the same radial distance from the axis of the post 36. By means of a drive member 46, shown in Figure 11, the outermost disk 45 is interconnected with the adjusting knob 42 which is mounted externally of the lock. The member 46 is provided with holes 46b, one of which engages a lug 45b projecting from the face of tumbler 45, as seen in Figure 6. Thus, by rotating the knob 42, first in one direction and then in the other, the three disks are eventually adjusted with their notches, such as the notch 35a, in alignment, to receive the nose 22 of the pawl 20. This releases the pawl from engagement with the lug 17 so that upon rotation of the disks in unison and in clockwise direction, the pawl, being engaged with the notches of the disks, draws the bolt back to unlocked position.

By reverse rotation of the outer tumbler 45, which is directly connected to the knob 42, as described, the pawl 20 is driven toward the left,

as viewed in Figure 5, for projecting the bolt 3 to locking position. In Figure 5 the tumblers 35 and 45 are omitted, and the parts are shown with the bolt partly moved toward locking position. As this movement progresses the tumbler 25 is arrested in its rotation by engagement of its peripheral abutment shoulder 25^a with the end of a spring 39, but the continued rotation of the upper tumbler 45 forces the nose 22 of the pawl 20 to climb the curved edge of the notch 26 in tumbler 25, which thus acts as a cam to force the latch out of the tumbler notches.

The spring 39 is approximately Z-shaped, with its upper end presented adjacent the edge of the disk 25 and with its lower end anchored by a stud 40 secured to the body of the bolt 3 within the casing 1. As the bolt advances in one direction, and the shoulder 25^a of the disk moves approximately in the opposite direction, the spring 39 is first stressed and bent somewhat out of its normal shape, as shown in Figure 5. Then, at the instant when the cam action of the flaring edge of the notch 26 in disk 25 forces the nose 22 out of the disk notches, the stress stored in the spring 39 is relieved and acts to rotate the disk 25 in reverse direction, thus carrying its notch 26 entirely out of registration with the nose 22 of the pawl 20, and providing support for the pawl on the circular portion of the periphery of the disk 25. The spring 39 thus acts automatically to "upset" or disarrange the registered relation of the disks 25, 35 and 45. And with the nose of the pawl 20 supported on the circular peripheries of the tumbler disks, the end of the pawl abuts the lug 17 which, in turn, is held fixedly at the position shown in Figure 5 by its engagement with the plate 6, cam 5 and spindle 4, because the spindle is interconnected with the plug of a cylinder lock and held against rotation thereby, as will be described presently.

The lock mechanism thus far described is enclosed in the casing 1 and may be secured therein by a cover plate 41, as seen in Figure 6. This then constitutes a unit of the mechanism which may be sealed for shipment and handling. The other unit is also shown in Figure 6 as consisting of the operating knob 42 with the mechanism contained therein, and with the escutcheon plate 43 in which the knob is rotatably mounted, and in which it is retained by a back plate 44 which may be permanently secured in position by "staking" or peening over the annular bosses 43^a which are cast integrally as a part of the escutcheon 43 and extend through apertures in the back plate 44. The annular bosses 43^a encircle countersunk apertures 47 in the escutcheon plate which register with apertures 2^a in the lugs 2 of the lock casing 1, while corresponding apertures 48 will be provided in the door panel 49 on which the lock is to be mounted. Thus the two units, the casing 1, with its enclosed mechanism, and the knob and escutcheon, with their enclosed parts, may be assembled on opposite faces of the panel 49 and clamped in operative relation by securing bolts extending through the apertures 47 and 2^a.

When the units are thus assembled the notched end of the hollow post 36 interlocks with correspondingly shaped prongs 50 projecting from the end of the cylindrical lock casing 51 on which the knob 42 is rotatably journaled. The casing 51 is thus held stationary at all times, while the key plug 52 within it may be turned by means of a suitable key for rotating its stem or spindle 53 which has a flattened bore 54 in which the

flattened terminal 4^a of the spindle 4 is interlocked when the units are assembled.

An annular, cup-shaped member 55 is rotatably fitted over the inner end of the cylindrical casing 51 and is provided with a pair of prongs which interlock with the notched hub 46^a of the tumbler driving member 46. The member 55 is normally connected to the knob 42 by means of a ball 57 acting as a clutch member by virtue of the fact that it fits in a hole 58 in the annular part 55 and projects into a recess 59 in the knob, as seen in Figure 7. In this position the ball is just even with the inner circumference of the annular part 55 and thus rides on the outer circumference of the end portion of the lock casing 51 when the member 55 is rotated thereon by turning of the knob 42 for adjusting the disk tumblers 45, 35 and 25 of the combination mechanism or actuating the bolt 3, as already described.

It may be understood that the knob 42 may carry an index mark, and the escutcheon 43 may include a graduated dial, or that the escutcheon may be provided with an index mark, and suitable graduations carried by the knob 42 as, for example, on its conical surface 42^a for guiding the user in adjusting the combination disks by rotative movements of the knob 42 in a well understood manner. With the three tumblers 35 as herein shown, this will involve setting the knob successively at three different dial readings which constitute the so-called "combination" of the lock. The user of the locker or other closure to which the lock is applied having then memorized these readings, can operate the lock at will without the use of a key.

Whenever it is desired to change the effective combination it will be evident that this can be done by securing the knob to the annular member 55 (and thus to the tumbler 45) in a different angular relation, so that a given portion of the tumbler 45, such as its notch or its lug 38, will stand opposite a different dial reading on the knob at 42^a. Such angular re-adjustment of the knob with respect to the member 55 is accomplished by means of a suitable reset key adapted to turn the key plug 52 through an angle of 90 degrees. The casing 51 is formed with a radial guideway 60 which is positioned for registration with the hole 58 in the annular member 55. A plunger 61, fitted in the guideway 60, normally bears against the cylindrical surface of a part 62 secured to the end of the key plug 52 and rotatable therewith. The plunger 61 is of such a length that in this position it will uphold the ball 57 in its clutching position; but the part 62 is formed with a recess or pocket 63 which may be brought into registration with the guideway 60 by rotation of the key plug through an angle of 90 degrees from its normal locked position. When this is accomplished, as shown in Figure 8, the plunger 61 can recede into the pocket 63, which is of such a depth that the ball 57 is thus permitted to withdraw entirely from the recess 59 in the knob 42, thus leaving the knob free to be turned upon the annular member 55. As seen in Figure 7, the knob is provided with a series of recesses 59 disposed at uniform angular intervals in its inner surface, and when the clutch ball 57 has been thus disengaged from one of the recesses 59 the knob may be turned to bring any other of these recesses into registration with the ball 57. Then, by reversely rotating the key plug 52 through an angle of 90 degrees, the plunger 61 will be forced out of the pocket 63 and will shift

the ball 57 into the newly aligned recesses 59, thus reconnecting the knob 52 with the annular member 55 and with the tumbler disk 45 at the new position corresponding to a new series of dial readings at which the knob must be set for operating the lock.

Each of the recesses 59 includes a pair of divergent faces, both obliquely intersecting the adjacent inner surface of the knob. In the positions of the parts shown in Figures 7 and 8 it happens that the ball 57 and plunger 61 would be shifted by gravity into the pocket 63 and out of the recess 59, but if the lock happened to be installed in inverted position or in a position at 90 degrees to that illustrated in these views, then upon registration of the pocket 63 with the guideway 60, a slight turn of the knob 42 would serve to cam the ball 57 out of the recess 59 and clear of the knob so as to permit the latter to be turned freely to any new position of adjustment. Then one or the other of the oblique faces of the pocket 63 would also operate as a cam against the rounded end of the plunger 61 to shift the plunger and the ball 57 back into clutching position.

Figure 9 shows the key plug 52 with the special reset key 70 inserted therein for thus turning the plug through an angle of 90 degrees to shift the pocket 63 into registration with the plunger 61, as thus described. This operation is controlled by cutting the key 70 to retract all the tumblers of the key plug 52 except one, which is indicated, at 71 as projecting in locking position. However, the casing 51 is formed with an arcuate groove 72 in registration with the tumbler 71 and extending 90 degrees circumferentially within the casing 51 so as to permit this measured rotation of the plug and thus insure accurate registration of the pocket 63 with the plunger 61.

Figure 10 shows the condition which accompanies insertion of the regular master key 80 for operating the bolt 3 by means of the spindle 4 and cam 5. As already explained, this requires only a limited angular movement of the cam 5 to bring its contact point 8 to the point 11 in the outline of the opening in the follower plate 6. As illustrated, this is an angle of about 50 degrees. Accordingly, when the regular master key 80 is inserted in the key plug 52, a single tumbler 81 is left projecting in locking position, but the casing 51 of the cylinder lock is formed with an arcuate clearance groove 82 registering with the projecting end of the tumbler 81 and extending substantially 50 degrees around the casing. Since the master key 80 withdraws all the remaining tumblers from locking engagement with the usual grooves 83, the plug 52 may now be rotated through an angle of 50 degrees for withdrawing the bolt 3, and such rotation will be limited by the arcuate groove 82 so as to prevent shifting the pocket 63 into registration with the plug 61 and thus releasing the knob from its adjusted relation to the combination mechanism.

It will be noted that, as shown in Figure 11, the notch 46^c in the hub 46^a of the driving member 46 is shorter in circumferential direction than the notch 46^d, and it may be understood that the prongs 56 which engage these notches are correspondingly different in extent. This insures that the driving member 46 can be connected to the annular member 55 in only one way when the two units of the lock shown in Figure 6 are brought together and thus makes it certain that the operating combination determined at the factory will be correct when the lock has been installed. This combination can be easily varied through a

series of locks in manufacture by assembling the member 46 so that a different hole of its flange registers with the lug 45^b in each of the locks respectively; and, of course, by other well-known expedients a very large range of combinations can be secured in this type of lock.

Figure 12 illustrates a modification of the detent member 32 shown in Figure 2. In the modified form the detent 32^x is made entirely of a single piece of spring wire which thus combines the function of the spring 32^a with that of the detent itself. This part includes a straight portion 32^y which extends from the side wall of the case to the stationary boss 36 and terminates in a part 32^z curled about the post. At the other end the wire is bent to provide oblique portions 33^x and 34^x corresponding to the cam faces 33 and 34 of the detent 32. This arrangement represents some economy in manufacture.

While there is shown and described herein certain specific structure embodying the invention, it will be manifest to those skilled in the art that various modifications and rearrangements of the parts may be made without departing from the spirit and scope of the invention, and that the same is not limited to the particular form herein shown and described, except in so far as indicated by the appended claims.

I claim as my invention:

1. In a lock which includes a bolt and a casing in which it is movable, means for moving the bolt comprising a cam pivoted to swing in the casing and a follower cooperating therewith, the cam being formed with a portion which provides contact points at two opposite sides of said portion and the follower having two separated surfaces both transverse to its direction of travel and formed to maintain contact simultaneously with said opposite sides of the cam respectively during movement of the bolt thereby, said sides of the cam being connected by an arcuate portion concentric with the pivot axis of the cam and the follower having a clearance opening formed to permit limited rotation of the cam after said arcuate portion passes the end of one of said surfaces, whereby the cam may then continue to turn without moving the follower and the bolt.

2. In a lock including a case, with a bolt slideable therein, a plurality of notched tumbler disks rotatable in the case, and a pawl connected to the bolt and engageable in the tumbler notches when they are adjusted in registered relation, whereby rotation of the tumblers in one direction serves to shift the bolt to unlocking position and reverse rotation of the tumblers shifts the bolt back to locking position, a unitary flexible spring member mounted in position for positive engagement with at least one of the tumblers during its reverse rotation, and formed to be flexed and stressed by said reverse movement, together with means which ejects the pawl from the tumbler notch upon completion of the bolt locking movement, whereupon said stressed spring forcibly rotates the said tumbler out of registered relation.

3. In the combination defined in claim 2, said spring member being mounted on the bolt with one end secured fixedly thereto and its other end disposed for said positive engagement with the tumbler.

4. In a lock including a case, with a bolt slideable therein, a plurality of notched tumbler disks rotatable in the case, and a pawl connected to the bolt and engageable in the tumbler notches when they are adjusted in registered relation, whereby rotation of the tumblers in one direc-

tion serves to shift the bolt to unlocking position and reverse rotation of the tumblers shifts the bolt back to locking position, an approximately Z-shaped flexible spring having one end anchored on the bolt, at least one of the tumblers having a peripherally disposed shoulder which encounters the other end of said spring during the reverse rotation of the tumbler, whereby the spring is flexed and stressed by said reverse movement, together with means which ejects the pawl from the tumbler notches upon completion of the bolt locking movement permitting the stressed spring to forcibly rotate the said tumbler out of registered relation.

5. In a lock which includes a bolt and combination mechanism adjustable for operating the bolt, independent operating means for the bolt including a key controlled cylinder lock comprising a key plug and a casing, a knob having a plurality of recesses spaced at intervals around its inner surface and clutch means normally connecting said knob with the combination comprising an annular member fitting within said surface of the knob and carrying a movable clutch element formed to engage any of said recesses, the casing of the cylinder lock fitting rotatably within said annular member and normally supporting said clutch element in engagement with a recess of the knob, means operable by the rotation of the key plug in its casing to provide a pocket with which the clutch element is registerable upon rotation of the knob, each recess of the knob having divergent faces obliquely related to the adjacent surface of the knob and operating to cam the clutch element out of the recess and into said pocket upon registration of said recess and pocket and rotation of the knob, thus freeing the knob for rotative adjustment on the annular member to alter its relation to the combination mechanism.

6. In a lock which includes a bolt and combination mechanism adjustable for operating the bolt, independent operating means for the bolt including a key controlled cylinder lock comprising a key plug and a casing, a knob having a plurality of recesses spaced at intervals around its inner surface and clutch means normally connecting said knob with the combination comprising an annular member fitting within said surface of the knob and the clutch member fitting in a hole in said annular member and engageable with any of the recesses, the casing of the cylinder lock fitting within said annular member and normally supporting said clutch member in the annular member and in engagement with one of said recesses of the knob, said lock casing having an opening registerable with said clutch member and a plunger slidably occupying said opening, together with a cam rotatable by the key plug within the casing opposite said opening and in engagement with said plunger, a portion of said cam being formed to permit the plunger to recede toward the axis of the cam so that said opening in the casing is available to receive the clutch member permitting the latter to withdraw from the recess of the knob, each recess of the knob having divergent faces obliquely related to the adjacent inner surface of the knob and operable to cam the clutch member out of the recess and into said opening upon rotation of the knob for adjustment on the annular member to register a

different recess with the clutch element for engagement thereby so as to alter the relation of the knob to the combination mechanism.

7. In a lock which includes a bolt and combination mechanism adjustable for operating the bolt, independent operating means for the bolt including a key controlled cylinder lock comprising a key plug and a casing, a knob and clutch means normally connecting said knob with the combination mechanism, said independent means being operable by rotation of the key plug through a limited angle in a certain direction by means of a proper key, a clutch controlled device operable by rotation of the key plug in the same direction but through a greater angle by means of a reset key for releasing the knob from the combination mechanism to permit resetting said knob in relation thereto.

8. In a lock which includes a bolt and combination mechanism adjustable for operating the bolt, independent operating means for the bolt including a key controlled cylinder lock comprising a key plug and a casing, a knob and clutch means normally connecting said knob with the combination mechanism, said independent means being operable by rotation of the key plug through a limited angle in a certain direction by means of a proper key, a clutch controlled device operable by rotation of the key plug in the same direction but through a greater angle by means of a reset key for releasing the knob from the combination mechanism to permit resetting said knob in relation thereto; said plug including a pair of tumblers one of which is left projecting when the plug is operated by said proper key and the other of which is left projecting when the plug is operated by the reset key, and the casing having arcuate grooves registering with said tumblers respectively and of different angular extent, whereby the end of each groove engages its tumbler to check rotation of the plug, one groove stopping said movement at the limited angle for independent operation of the lock and the other groove stopping said movement at the said greater angle required for resetting the knob.

9. In a lock which includes a bolt and combination mechanism adjustable for operating the bolt, independent operating means for the bolt including a key controlled cylinder lock comprising a key plug and a casing, a knob and clutch means normally connecting said knob with the combination mechanism, said independent means being operable by rotation of the key plug through a limited angle in a certain direction by means of a proper key, a clutch controlled device operable by rotation of the key plug in the same direction but through a certain greater angle by means of a reset key for releasing the knob from the combination mechanism to permit resetting said knob in relation thereto, together with means rendered operative by said proper key to restrict rotation of the plug to said limited angle insufficient to actuate the clutch controlled device.

10. In the combination defined in claim 9, additional means rendered operative by said reset key to restrict rotation of the plug to said greater angle at which the knob is releasable from the combination mechanism.

WILLIAM E. HAMILTON.
